DESIGN FOR A DRESS

Joseph Lipof, Mattapan, Mass.

Application December 30, 1938, Serial No. 82,064

Term of patent 3½ years

To all whom it may concern:

Be it known that I, Joseph Lipof, a citizen of the United States and a resident of the city of Mattapan, in the county of Suffolk, State of Massachusetts, have invented a new, original, and ornamental Design for a Dress, of which the following is a specification, reference being had to the accompanying drawing, constituting a part thereof.

Fig. 1 is a front view of a dress showing my new design.

Fig. 2 is a rear view of the dress shown in Fig. 1.

The characteristic feature of my design resides in the combination on the square necked surplice dress disclosed of the cartridge tucking on the yoke and sleeves in association with patch shirring at the front waistline and a panel of button trimmed pleats on the side of the skirt, as shown.

The ornamental design for a dress, substantially as shown and described.

I claim:
